UNITED STATES PATENT OFFICE.

CLARENCE J. HATFIELD, OF BUCKNER, MISSOURI.

PLOW-POINT TONGS.

1,201,462.

Specification of Letters Patent. Patented Oct. 17, 1916.

Application filed June 15, 1916. Serial No. 103,760.

To all whom it may concern:

Be it known that I, CLARENCE J. HATFIELD, a citizen of the United States, residing at Buckner, in the county of Jackson 5 and State of Missouri, have invented certain new and useful Improvements in Plow-Point Tongs; and I do declare the following to be a full, clear, and exact description of the invention, such as will enable others skilled in the art to which it appertains to 10 make and use the same.

My invention relates broadly to improvements in tongs such as those used by blacksmiths and other metal workers and the object thereof is to provide a simply constructed tool which will operate to great advantage for holding a plow point while sharpening the nose thereof after it has become dulled.

With this general object in view, the invention resides in certain novel features of construction and unique combinations of parts to be hereinafter fully described and claimed, the descriptive matter being supplemented by the accompanying drawing which constitutes a part of this application and in which:

Figure 1 is a bottom plan view of a plow point showing the application of the invention thereto; Fig. 2 is a side elevation of the tool showing an edge view of the point held thereby; Fig. 3 is a perspective view of the improved tool; Fig. 4 is a detail transverse section of one of the jaws thereof.

In specifically describing the structure shown in the drawing above briefly described, similar characters will be employed to designate corresponding parts throughout the several views and reference will be herein made to the numerous elements by their respective indices. To this end, the numerals 1 and 2 designate a pair of steel or iron bars crossed near their front ends and pivoted together at 3. The front end 40 of bar 1 is flattened and is preferably straight to form a jaw 4 disposed obliquely of the body portion of said bar, this jaw being adapted for contact with the upper side 45 of a plow point P as shown clearly in Fig. 50 2. The jaw 4 is preferably channelled

longitudinally on its working face as indicated at 5 to permit better engagement thereof with the plow point. At the point 6 the front end of the bar 2 is bent outwardly away from the working face of the 55 jaw 4 and is then bent inwardly to form a U 7 adapted to straddle the land side flange F of point P, the free end of said U having a cross head 8 formed integrally therewith and positioned obliquely of the jaw 4, said 60 U being disposed in approximately the plane of said jaw, that is, it extends obliquely of the tool to about the same degree as this jaw. The head 8 constitutes a second jaw adapted to contact with the inner side of the flange 65 F and with the lower side of the point P, said head preferably having a flat working face as shown.

To retain the flange F in or substantially in contact with the head 8 and thus prevent 70 turning of the point P between the jaws, a curved finger 9 is formed integrally with the fixed end of the U 7, said finger being adapted to contact with the outer side of the aforesaid flange and having its free end 10 75 disposed at any suitable point between the ends of the head 8.

By constructing the improved tongs in the manner shown and described, they will be highly efficient and durable and will fulfil 80 a long felt need in that a plow point may be readily held thereby while sharpening the earth penetrating nose thereof.

I claim:

A tool for holding plow points, said tool 85 comprising a pair of bars crossed and pivoted together near their front ends, the front end of one bar being disposed obliquely of the remainder of said bar and being substantially straight to form a jaw for contact 90 with the upper face of the plow point, the front end of the other bar being bent outwardly away from the working face of the aforesaid jaw and being then extended inwardly toward said jaw to form a U adapt- 95 ed to straddle the land side flange of the point, the free end of said U having thereon a cross head constituting a second jaw extending obliquely of the other and adapt- 100 ed to contact with the lower face of the

point and with the inner side of said flange, the fixed end of said U having formed thereon a laterally extending finger adapted to contact with the outer side of the aforesaid flange to retain the latter in contact with said second jaw and thus prevent turning of the point within the tool.

Copies of this patent may be obtained for five cents each, by addressing the "Commissioner of Patents, Washington, D. C."

In testimony whereof I have hereunto set my hand in the presence of two subscribing witnesses.

CLARENCE J. HATFIELD.
